SHOE POLISHER

Burton S. Dake, Jr., Altadena, and Paul S. Weersing,
Glendale, Calif., assignors to Plastics, Inc., Pasadena,
Calif., a corporation of California

Filed Mar. 29, 1963, Ser. No. 74,218

Term of patent 3½ years

(Cl. D9—2)

FIG. 1

We claim:

The ornament design for a shoe polisher, as shown.
